UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION OF COPARTNERSHIP, HAVING AS TRUSTEES F. B. TOWNE, E. S. TOWNE, J. M. TOWNE, AND F. W. WILSON.

POST BINDER FOR LOOSE-LEAF SHEETS.

Application filed June 11, 1924. Serial No. 719,284.

To all whom it may concern:

Be it known that I, JOHN SCHADE, a citizen of the United States, residing at the city of Holyoke, in the county of Hampden 5 and State of Massachusetts, have invented certain new and useful Improvements in Post Binders for Loose-Leaf Sheets; and I do declare the following to be a full, clear, and exact description of the invention, such 10 as will enable others skilled in the art to which it appertains to make and use the same.

This invention relates to what are known as "post binders" for loose leaf sheets, but more particularly relates to the method of forming the flat tubular cheek pieces of such binders and providing them with hinge lugs.

Referring to the accompanying drawing— 20 Figure 1 is a detail perspective of the tubular member partially closed preparatory to the securing of the hinge lugs.

Figure 2 a cross section of the tubular member shown at Figure 1 with one of the 25 hinge lugs in position.

Figure 3 an end view of the completed article.

Figure 4 a view similar to Figure 2 but showing a modification of the manner of 30 securing the hinge lugs.

Figure 5 a detail perspective of a hinge lug such as would be used in the structure noted at Figure 4.

Figure 6 is a broken view of a blank 35 such as would be used in a modification for the formation of the tubular cheek piece, and

Figure 7 is a cross section of the completed article showing the hinge lug secured 40 within a cheek piece made from the blank shown at Figure 6.

Similar numerals of reference denote like parts in the several figures of the drawing.

This invention is of the same general nature as that set forth in the application heretofore filed by me February 26, 1924, under Serial No. 695,219, and is more particularly intended as an improvement upon the structure shown in said application.

50 In the present invention the tubular cheek

piece 1 is blanked out of sheet metal pierced to form elongated openings 2 (only one shown) parallel of its length and midway between its sides, and the blank is then partially bent into shape so as to leave the free 55 ends angularly disposed with respect to each other, as shown at Figure 1. The hinge lug 3 is then inserted between these ends through the opening 2 so as to cause the eye or closed portion of the lug to project outside of the opening 2, while the diverging ends 4 of the lug lie against the inner faces of these ends adjacent the opening 2, and these diverging ends are then electrically 60 welded to said angularly disposed members, 65 which latter are then bent into closed position with their outer edges in close abutment, thus forming the completed flat tubular member. This operation of welding is 70 very conveniently performed owing to the fact that the tube is not fully closed but has the angularly disposed portions.

It is not absolutely essential that the diverging ends of the hinge lug be welded to the tube, since the blank 8 from which 75 the tube is shaped may be formed with small openings 7 within which the extremities of the diverging ends of the lug will snap when the lug has been inserted through the opening 2, this construction being fully shown 80 in Figure 6 and Figure 7, and in this connection the ends of the lugs would diverge more sharply as shown at Figure 5.

What is claimed is:—

The method of forming the tubular members of post binders for loose leaf sheets with hinge lugs, which consists in forming a rectangular blank and simultaneously cutting elongated openings therein parallel of its length and midway between its sides, bending said blank on a line with said openings with the bent portions diverging, inserting in said openings hinge lugs, welding the free ends of said lugs to the inside of the partially completed tube, and finally bending 95 said portions into completed form with their edges in close abutment.

In testimony whereof I affix my signature hereto.

JOHN SCHADE. 100
